UNITED STATES PATENT OFFICE.

GEORGE N. PIFER, OF CLEVELAND, OHIO, ASSIGNOR TO THE AMERICAN AUTOMATIC PHOTOGRAPH COMPANY, OF CLEVELAND, OHIO, A CORPORATION OF OHIO.

LOADING DEVICE FOR AUTOMATIC PHOTOGRAPH-MACHINES.

SPECIFICATION forming part of Letters Patent No. 794,639, dated July 11, 1905.

Application filed January 14, 1904. Serial No. 189,034.

To all whom it may concern:

Be it known that I, GEORGE N. PIFER, a citizen of the United States, residing in Cleveland, Ohio, have invented certain Improvements in Loading Devices for Automatic Photograph-Machines, of which the following is a specification.

My invention consists of certain improvements in the means for loading automatic photographic apparatus shown and described in my Patent No. 708,164, dated September 2, 1902, the objects of my present invention being to simplify and cheapen the construction of the plate-holder and of the removable closure whereby the plates are normally retained therein, and to increase the capacity of the holder, so as to provide for a much greater number of exposures than before, without the necessity of recharging the machine.

In the accompanying drawings, Figure 1 is a sectional view illustrating my improved plate-holder and those parts of an automatic photograph-machine in connection with which said plate-holder is intended to be used, the parts being shown in the position occupied by them when the holder is first introduced into the machine and before the removal of the temporary closures, whereby the plates are normally retained in the holder. Fig. 2 is a similar view showing the temporary closures removed and the plates in position for being fed into the machine. Fig. 3 is a transverse section on the line *a a*, Fig. 2. Fig. 4 is a plan view of the device shown in Fig. 3. Fig. 5 is a sectional view illustrating a single plate-holder constructed in accordance with my invention; and Fig. 6 is a sectional view of the lower portion of a plate-holder, illustrating a modified form of removable closure therefor.

In the drawings, 1 represents part of the fixed internal structure of an automatic photograph-machine, said structure providing a slideway for the reception and guidance of a slide or pusher 2, whereby the sensitive plates are fed successively into the machine

from a holder revolvably mounted upon the structure 1. This holder consists in the present instance of a cylindrical block 3, 50 having therein four vertical cylindrical bores 4, each permanently closed at the top, said block being composed of paper, wood, or other material which will combine the qualities of lightness and cheapness. The block 3 55 is preferably formed with a central opening in the bottom for the reception of the upper end of a short vertical shaft or spindle 5, which has a bearing upon the structure 1 of the machine and is provided below the same 60 with a ratchet-wheel 6, with which is adapted to engage a pawl 7, pivotally mounted upon the sliding pusher 2, so that as the latter is reciprocated intermittent movements of partial rotation will be imparted to the 65 ratchet-wheel 6, and hence to the block 3. Each of the bores 4 in said block carries a column of sensitive plates 8, which are in the first instance fed face downward into said bores while the block 3 is held in an inverted 70 position, a ball or other weight 9 being first inserted in one of the bores for a purpose described hereinafter. When each of the bores 4 in the inverted holder has been filled almost to the top with the sensitive plates 8, 75 each bore is closed by means of a concavo-convex disk 10, of rubber or other flexible material, which fits snugly against the walls of the bore and by reason of its frictional hold upon said walls not only retains its position in the bore against the pressure exerted upon it by the column of plates when the holder has been turned right side up, but it also serves to seal the bore against the entrance of light. The concavo-convex disk 10 has secured to it a looped cord or wire 11, which when the disk has been properly applied to the bore of the tube projects beyond said disk, as shown in Fig. 1.

In applying the plate-holder to the machine the central opening in the bottom of the same is fitted upon the projecting upper end of the shaft or spindle 5, which may, if desired, be square or otherwise shaped, so as

to fit a correspondingly-shaped opening in the holder, and thus insure rotation of the latter when the shaft or spindle is rotated. When thus adjusted, one of the bores of the 5 plate-holder is vertically in line with an opening 12 in the lower portion of the structure 1, which opening is of lesser diameter than the diameter of the plate-holder bore or of the sensitized plates contained therein. The 10 temporary closure 10 of said bore of the plate-holder can therefore be readily removed by means of a suitable implement engaging the looped cord or wire 11 of each closure, a downward pull upon said loop drawing downward the center portion of the flexible disk 10, so as to first reverse the direction of its concavity and then withdraw the disk through the opening 12, the lowermost plate of the column of plates in the bore dropping 15 onto the support afforded by the structure 1, and by partially rotating the block 3 another of its columns of plates can be brought into line with the opening 12, the closure 10 removed, and so on until all of said closures 20 have been withdrawn. As the first of the free columns of plates comes over the opening 13 in the pusher-slide 2 it drops into said opening, so as to be ejected when the pusher-slide is projected. As the pusher-slide 2 is 25 reciprocated so as to eject the plate movement to the extent of a quarter-turn is imparted to the ratchet-wheel 6 and plate-holder 3, so as to bring another column of plates into position to feed its lowermost 30 plate into the opening 13 of the pusher-slide when the latter is retracted, and this operation is repeated on each reciprocation of said pusher-slide until all of the plates in all of the bores of the holder are discharged, the final 35 action being to permit the ball or weight 9 to drop through the opening 13 and through an opening 14 in the structure 1 for the purpose of tripping the cut-off device of the machine.

My invention is, as will be evident, applicable to plate-holders having a single bore equally as well as to plate-holders having a plurality of bores, and in Fig. 5 I have illustrated such single plate-holder 3^a, which instead of being supported upon a revoluble 40 shaft has a shoulder 15 resting upon a tube 16, which is supported upon a portion of the fixed structure of the machine and extends down to or supports the structure 1, in which the pusher-slide is guided. Either the support 45 of the plate-holder upon the shaft 5, as in Figs. 1 and 2, or the support of the single holder by means of its shoulder 15 upon the tube 16 relieves the pusher-slide from the weight of the holder, and thereby lessens the 50 friction upon said slide which would interfere with its free reciprocation.

In carrying out my invention also other forms of externally-accessible closure for the plate-holder may be employed. For instance, 55 in Fig. 6 I have shown the open end of the

plate-holder 3^a provided with a temporary closure consisting of a flat disk 17, secured to the lower end of the holder by means of a strip or sheet 18 of thin paper, so that after the holder has been properly inserted into the receiving-tube 16 of the machine the closure 17 can be readily removed either by the action of the pusher-slide 2 or by a similar device which will tear or sever the thin paper-retainer, whereby the disk is normally held in place and will thus permit said disk to be thrust transversely away from the lower end of the tube, so as to permit of the descent of the plates in the holder and their delivery from the open end of the same. 80

By providing a holder for the plates with a temporary and removable closure accessible from the outside of the holder the necessity of providing the holder with a movable cap or other movable member at its upper 85 end, as in my previous patent, No. 708,164, is rendered unnecessary and the construction of the holder is simplified and cheapened, since the same can be made of wood or paper in one piece instead of being constructed of metal in more than one piece. Hence the holder when empty can be discarded instead of being returned for refilling. Furthermore, the operation of the holder is not interfered with by the rusting in place of a metallic cap. 90 Hence the improved holder is more certain in its action than the patented holder, and the temporary closure now employed is also materially simplified and cheapened as compared with a closure of the character shown 95 and described in said patent.

By providing the machine with a plate-holder carrying a plurality of columns of plates the capacity of the same is correspondingly increased, thereby resulting in a 100 desirable increase in the number of exposures permitted between successive chargings of the machine.

Any desired form of movable carrier for conveying the plate from the plate-holder to 105 the point of discharge may be used, the reciprocating pusher being simply one form of device available for the purpose.

Having thus described my invention, I claim and desire to secure by Letters Patent— 115

1. Means for loading a photographic apparatus, comprising a receptacle for carrying a column of photographic plates and a removable closure at one end of said receptacle, 120 said closure having a portion accessible from the outside of the receptacle, whereby it can be removed by external means, substantially as specified.

2. Means for loading a photographic apparatus, comprising a receptacle for carrying a column of photographic plates, said receptacle being permanently closed at one end and having a removable closure at the opposite 125 end, which closure has a portion accessible 130

from the outside of the receptacle, whereby it can be removed therefrom by external means, substantially as specified.

3. Means for loading a photographic apparatus, comprising a receptacle for containing a column of photographic plates and a removable closure for one end of said receptacle, said closure comprising a disk of flexible material, having a downwardly-extended portion whereby it can be engaged by externally-operating means to effect removal of said temporary closure, substantially as specified.

4. Means for loading a photographic apparatus, comprising a receptacle for carrying a column of photographic plates and a disk of flexible material serving as a temporary closure at one end of said receptacle, said disk having a looped cord or wire engaging the same and extending downwardly from said disk, substantially as specified.

5. Means for loading a photographic apparatus, comprising, in combination, a receptacle carrying a plurality of columns of photographic plates, a movable pusher, and means for mounting said receptacle so that it is movable in respect to said pusher, whereby the columns of plates may be

brought successively into position to feed the pusher, substantially as specified.

6. Means for loading a photographic apparatus, comprising, in combination, a receptacle carrying a plurality of columns of photographic plates, a movable pusher, and means for revolvably mounting said receptacle, whereby its columns of plates may be brought successively into position to feed the pusher, substantially as specified.

7. Means for loading a photographic apparatus, comprising, in combination, a receptacle carrying a plurality of columns of photographic plates, a movable pusher, means for mounting the receptacle so that it can rotate, and means whereby the intermittent movement of the pusher is caused to impart intermittent movements of partial rotation to the plate-receptacle, substantially as specified.

In testimony whereof I have signed my name to this specification in the presence of two subscribing witnesses.

GEORGE N. PIFER.
